PUSHER MECHANISM FOR MATRIX ASSEMBLERS

Byrd S. Fine, Waterbury, Conn.

Application February 10, 1948, Serial No. 7,384

3. Claims. (Cl. 199—27)

1

This invention relates to the matrix assembling mechanism of a type composing and casting machine, and more particularly to an improvement of the matrix pusher mechanism shown in my prior Patent No. 2,163,390 of June 20, 1939.

A type composing, setting and casting machine of the standard type has an elevator provided with spaced rails on which the matrices are assembled automatically. These matrices are released selectively from a supply magazine in accordance with the operation of a keyboard and fall onto a traveling belt together with spacers, herein termed matrices, and they are delivered serially to the elevator rails on which they are stacked. When the line of matrices on the rail is full, then the elevator is raised to a point where the matrices are delivered to further mechanism arranged for casting a molten type metal into the characters on the matrices. The elevator loading mechanism comprises a star wheel that is rotated in such a way as to thrust the matrices serially along the elevator rails and behind spring pressed latches located at the near end of the rails. The star wheel may not succeed in pushing the last matrix of the line into position so that the matrix may fall laterally and hamper the elevator movement or cause the line to be ejected from the rails. In order to insure proper assembly, I have provided a secondary pusher, in accordance with my prior patent, which thrusts the last matrix into position between the latches.

My prior mechanism comprises a pivoted arm held out of an operative relation to the last matrix by a lever, which is positioned by engagement with a part on the bottom of the elevator. When the elevator starts upwardly, that lever is released and a spring moves the pusher forward to strike the last matrix; but the pusher necessarily remains in that position until after the elevator has come back to its lowermost position. It is necessary at times that the elevator be lowered manually by the machine attendant, if he finds that there is an error in the line of matrices and wants to correct the error. However, the pusher remains in its forward operative position between the elevator rails after the matrices have been removed therefrom. Normally, the elevator may return to its lowermost position without interference on the part of the pusher because the latter passes between the rails. If, however, the matrices are left on the rails, as is the case when the elevator is lowered manually to correct an error, then the pusher will strike the underside of the matrices and eject them from the elevator or cause the mechanism to become jammed.

2

The primary object of my invention is to provide a supplemental pusher mechanism that will move the last matrix into position on the elevator slide rails, but which cannot interfere with the movement of the elevator in either direction.

A further object is to provide such a mechanism which is operated in timed sequence with the elevator movement but independently thereof and which is withdrawn quickly from its operative position as soon as it has effected its purpose.

Referring to the drawings which illustrate one embodiment of my invention:

Fig. 1 is a fragmentary side elevation, partly broken away, of the elevator rails and the matrix pushing mechanism in an inoperative position;

Fig. 2 is a top plan view, partly broken away, of the same; and

Fig. 3 is a fragmentary detail showing the pusher in its operative position.

In a construction of the type described in my prior patent, the matrices 10 are adapted to be mounted on the spaced slide rails 11 of the elevator and there held in position by two spring pressed clamping latches 12 suitably mounted on the rails. The matrices are normally pushed past the latches and moved along the rails by a positively rotated star wheel 13 in accordance with standard practice, but that star wheel sometimes fails to push the last matrix 14 (Fig. 1) into position. I, accordingly, provide a supplemental pusher 15 comprising the long curved arm shown in the drawing which is pivotably mounted on a stationary pivot 16 on the machine frame. The curved part of the pusher is shaped to be moved over the top of the star wheel and strike the top portion of that last matrix 14 and thrust it into place behind the spring latches 12.

The pusher 15 is moved after the line has been assembled and at about the time the elevator starts and preferably just before. This is best accomplished by a crank arm and linkage governed by the cam 16 that controls the elevator movement, or by other suitable mechanism that operates in a time relation with the elevator. In the construction illustrated, the rotatable cam wheel 16 has a short cam or lug 18 on its side that is shaped to strike momentarily and lift a cam follower or roller 20 mounted on the lower end 50 of a rock arm 21. The cam wheel is preferably the cam that causes the elevator movement as described in said patent, and the cam lug 18 is located to be lifted just in advance of initiation of the elevator movement upwards. The rock arm 21 is fixed on the end of a shaft 22 that is

suitably mounted in bearings on a U-shaped bracket 23 bolted to a part of the machine frame. The shaft 22 has a bell crank lever 25 secured on its far end by nuts threaded on the shaft. The upper end of this lever 25 has a stud 26 (Fig. 1) to which is fixed the end of a helical tension spring 28. The other end of that spring is connected to a pin or post 29 fixed on a long slide bar 30. That bar is pivotally connected at 31 to the bottom portion 32 of the pusher 15, which is a lever of the first class.

When the cam 18 of the cam wheel 16, which is traveling in the direction of the arrow of Fig. 1, strikes and swings the roller 20 towards the left, it swings the arm 25 towards the right and pulls through the spring 28 to move the bar 30. This thrusts the upper crook end of the pusher 15 forward towards the left into contact with the top of the last matrix 14. The crook end is of such length relative to the swinging movement that the matrix 14 is necessarily pushed into position during normal operation of the machine.

The bar 30 has a long slot 34 therein so arranged that the bar may slide on and relative to a fixed post 35 mounted on the machine frame. The post has a head projecting through the slot and thus locating that end of the bar. The post 29 on the bar 30 is connected to that fixed post 35 by a helical tension spring 36. This spring 36 is materially weaker than the other spring 28, and its purpose is to return the matrix pusher to an inoperative position as soon as the cam 18 has released the cam roller 20.

The cam 18 is short and acts only momentarily on the cam follower. Hence, the pusher 15 is moved forward only momentarily, while the cam 18 is passing the roller 20. As soon as the parts have moved out of contact, then the weak spring 36, which is secured between the fixed post 35 and the post 29 on the bar 30, serves to push that bar towards the left and thus rock the pusher 15 out of the path of the moving elevator, which at that time is just starting its upward journey. A stud 37 on the machine frame serves to prevent the pusher 15 from moving back too far. Hence, in that construction the pusher is moved forward under a yielding resilient force (spring 28) and it is returned to an inoperative position by another spring 36; but since the spring 28 is the stronger, the other spring cannot interfere with the forward movement of the pusher.

A further feature lies in the adjustment of movement of the bar 30 relative to the fixed post 35. This comprises a slide plate 40 that has a slot 41 within which is mounted a screw 42 that is threaded into the bar 30. The head of the screw rides against the slide plate 40 and thus serves to clamp that slide plate in any desired position of adjustment. This slide plate is arranged to project over the slot 34 to a required adjusted distance and thus limit the travel of the bar relative to the fixed post 35 on which the bar slides. This limits the forward motion of the bar 30 towards the right and thus serves as an adjustment of the final position of the end 45 of the pusher.

The operation of the mechanism has been explained above. The cam wheel 16 revolves in a timed relation with the other parts of the machine when a line of matrices has been assembled. That wheel serves to lift the elevator to present the line for a type casting operation. The short cam 18 is preferably located on the side of the cam wheel, so as not to interfere with

the elevator lifting mechanism. When the wheel 16 revolves in the direction of the arrow in Fig. 1, the rounded nose of the short cam 18 strikes the roller 20 on the rock arm 21 and moves the upper rock arm 25 momentarily to the right. This applies tension to the strong spring 28, which overcomes the opposing tension of the weak spring 36. This pulls the slide bar 30 to the right as far as is permitted by the position of adjustment of the slide plate 40 which strikes the stationary post 35 at the limiting position. Movement of the slide bar rocks the nose 45 of the pusher 15 into contact with the end matrix 14, and the distance of movement, as determined by the slide plate adjustment, is such that the matrix must move past the spring latches 12 on the elevator and so be locked in position in the line. As soon as the short cam 18 has passed the roller 20 and tension on the spring 28 is released, the weak spring 36 serves to slide the bar 30 to the left and remove the pusher from the path of movement of the elevator.

The pusher stays in an inoperative position during substantially the entire up and down movement of the elevator. Hence, if the machine attendant wants to lower the elevator by hand for any reason, he may do this without the pusher 15 being caught beneath the elevator as would be the case if the pusher were held in a forward operative position according to my prior construction. It is to be noted that the pusher is independent of the elevator although moved in timed relation therewith, since it is not moved by the elevator or any part connected to it. The pusher moves forward momentarily to accomplish its function and then quickly retreats, to lie idle until again needed. The elevator may be moved down and up manually without interference, and the pusher acts only when forced to do so by its cam 18. Also, since the pusher preferably acts before the elevator starts, the pusher can act positively to make sure that the last matrix is secured on the elevator before the latter starts to move.

Various other advantages are inherent in the construction as will be appreciated by one skilled in the art. Also, it will be understood that many modifications may be made in the construction without departing from the scope of the appended claims.

I claim:

1. In a type composing and casting machine having a vertically movable elevator on which a line of matrices is assembled, a supplemental pusher mechanism for pushing the last matrix into position comprising a pivoted pusher movable to contact with the last matrix, a cam independent of the elevator but moved in timed relation with the elevator movement, a cam follower moved by the cam at about the start of the elevator movement, a resilient member connecting the follower with the pusher to thrust the latter forward under the impulse of the cam and resilient means independent of the elevator movement for returning the pusher to an inoperative position out of the path of downward movement of the elevator.

2. In a type composing and casting machine having a movable elevator on which a line of matrices is assembled, a pusher mechanism for thrusting the last matrix of the line into position comprising a pivoted pusher lever movable to contact with the last matrix, a short cam independent of the elevator which is moved in timed relation with the elevator movement, a pivoted

cam follower moved by the cam at about the start of the elevator movement, means including a spring connecting the follower with the pusher to move it yieldingly into contact with the last matrix and thrust it into position, and a second spring weaker than the other which is connected to the pusher and yields during the matrix pushing operation but withdraws the pusher to an inoperative position as soon as the cam has passed the follower.

3. A device as covered by claim 2 comprising a slotted bar pivotally connected to the pusher which is resiliently connected to the follower by the stronger spring, a fixed member on the machine frame which is mounted in the bar slot for movement of the bar longitudinally thereon, the

weaker spring connecting said member with the bar to return the pusher to an inoperative position, and an adjustable member on the bar which limits the length of the slot and controls the forward movement of the pusher.
